MINING TOOL FOR INJECTING LIQUID, SUCH AS WATER, AT HIGH PRESSURE

Jean Jerusel, Waziers, France

Application February 20, 1957, Serial No. 641,371

Claims priority, application France February 21, 1956

6 Claims. (Cl. 262—34)

The present invention relates to a mining tool for injecting a liquid such as water at high pressure, for the purposes of dust-abatement and coal-winning in mines, or for a similar purpose involving the use of liquid under high pressure.

The invention is a mining tool for injecting into a bore hole a liquid, such as water, at high pressure, comprising a tubular body member having a valve-controlled injector nozzle and an abutment at one end, and at the other end region a movable abutment actuatable by the high pressure liquid, and resilient deformable means located between said abutments, so that on introduction of high pressure liquid into the bore of said tube, said movable abutment is urged towards said fixed abutment to compress axially and deform said resilient means which expand radially to engage the wall of the said bore hole to lock said tool in position before liquid is injected through said valve-controlled nozzle.

Preferably, said resilient means comprises a series of rings encircling said tubular body member, alternate rings being formed from rubber-like material and alternate rings being formed from metal.

Preferably, said movable abutment comprises a sleeve surrounding and spaced from said tubular member and movable as a ram under the action of high pressure liquid from the tube bore.

Preferably, said nozzle is controlled by a spring-loaded valve which opens at a predetermined pressure to permit injection.

An advantage offered by the invention is the rigid and reliable method of securing the tool in the vein or seam of coal in the case of coal-mining, which guards the operator against the well-known danger of a sudden recoil of the tool. A further advantage is that the tool in accordance with the invention can be extended by the addition of successive lengths of tube, whereby the tool can be inserted into and operated at a depth of rock considerably in excess of that heretofore obtained.

These advantages are made possible by,

(1) The mounting on the tool of a metal sleeve enclosing the tool over part of its length with provision between said sleeve and the tubular body of the tool of an intermediate chamber in which the water, admitted under pressure by a suitable device, constitutes a second sleeve of liquid, the pressure of which between the metal sleeve and the body of the tool producing a sliding displacement. The result of this sliding displacement is to compress longitudinally a certain number of rings of resilient material, the lateral expansion of which rings produces a rigid locking effect on the tool within the rocky soil into which it has been inserted. This locking effect increases correspondingly with increase of water-pressure in the tool;

(2) The provision, as required, of a number of additional lengths of tube which can be inserted between the body proper of the tool and the injector head or pump.

Other inventive features such as the terminal clack-valve, water-tight elements, etc., will be observed in the following description.

An embodiment of the invention will now be described,

2

by way of example, with reference to the accompanying drawing, in which:

Fig. 1 is an axial section of the body of a mining tool for use in dust abatement and in breaking down underground coal.

Fig. 2 is an axial sectional view showing an intermediate length of tube for extending the tool.

Fig. 3 is an axial sectional view showing an extension tube for attachment to an injector pump and,

Fig. 4 is an axial sectional detail view showing a valve device.

Referring to the drawing, each tubular element forming the body of the tool or extension piece, is illustrated showing only the two extremities thereof, the centre part of each being cut away for convenience.

The tool which will now be described is capable of injecting water at a pressure of approximately 200 kg./cm.² within a bore over a depth of approximately 15 meters.

In Fig. 1 the main part of the tool comprises essentially a straight, rigid tubular body 1. Water is conveyed under pressure, through the core 1 of the body following the arrow Z from the injector (not illustrated) towards the terminal orifice II controlled by the clack-valve 10 (the construction of the valve 10 will be described herein-after, in greater detail).

The tube 1 is threaded at both extremities 2 and 3. To the threaded portion 2, which is conventionally shown in the vicinity of the orifice II, collar 4 is screwed. Collar 4 receives, in turn, on its threaded portion 5, cap 6 to which nozzle 7 is screwed. The skirt 8 of the nozzle 7 acts as an abutment for coil spring 9 which normally urges valve 10 against the seating in collar 4. A milled screw 11 is provided in order to regulate, as desired, the longitudinal position of the nozzle 7 and consequently the pressure exerted by the spring 9 on the valve 10. This, therefore, offers a simple means of regulating the degree of resistance provided by the valve 10 to the ejection of water under pressure.

Two flats 12 on the seating 4 enable the seating to be rigidly secured to the tube 1 and also to be unscrewed when it is necessary to replace the resilient annular elements, which will be described hereinafter, after excessive wear. The tube 1 is ringed, between the seating 4 and the displaceable sleeve 21, by a plurality of annular elements, as shown in Fig. 1. Some of these elements are of a metal such as cast aluminium, and the others are of a resilient material such as rubber. The metal elements are referred to as 14, 14' . . . 14n, the resilient members as 15, 15' . . . 15n. These elements are located between and limited by the annular seating 4 at one end, and by the displaceable sleeve 21 at the other end.

The extremity of the tube 1 distant from the outlet orifice II, is threaded at 3 to receive a collar 16 for connecting the body of the tool either to the injector itself, or to a tubular extension piece, as will be explained. Two flats 13 provided on the outer surface of the tube enable it to be firmly screwed or unscrewed without damaging the tube. At the entry end of the water fed from the injector, the tube 1 is encased in a metal sleeve 21 of high tensile strength. The sleeve is at one end screwed to a ring 22 slidably carried on the tube 1 and terminates at the other extremity in an integral ring 27 having a toric seal or gland 28 capable of rolling against the tube. A further ring 23 is welded at 24 to the tube 1 and encloses a toric seal or gland 25 bearing upon the inner surface of the sleeve 21. On the other face of the ring 23, a resilient skirt-like seal 26 is disposed towards the outlet extremity of the tool.

The tube 1 is formed with a lateral bore 17 between the core 1 and chamber 20. Chamber 20 is limited by the outer face of the tube 1, the inner face of the

sleeve 21, the ring 27 and the seal 26 (the toric seals 25 and 28 improve tightness in order to prevent any losses of hydraulic pressure). The bore 17 is aligned with a hole provided in a ring 18. Ring 18 is locked onto the tube 1 by the screw 19 and forms an abutment to limit the recoil of the sleeve 21 by engaging the ring 27, or a forward thrust by engaging the seal 26. With the mechanism in this position, the tool is inserted into the bore and the water is conveyed at high pressure through the injector (direction of the arrow Z) into the tube 1. The water fills the tube without initially actuating the check-valve 10 which is held against its seating by the spring 9. The water under pressure then enters the chamber 20 to expand the chamber. Since the sleeve 21 is rigid, and the seal 26 is locked by the ring 23, the hydraulic pressure is exerted against the ring 27 to move the sleeve 21 in the direction of the arrow Z. The tube 21 slides along the tube 1 on the rings 22 and 27, the roller-like toric seals 25 and 28 accompanying said sliding movement.

The result of this displacement of the sleeve 21 on the tube 1 is to reduce the distance between the ring 27 and the valve-seating 4, and so compress the series of annular elements therebetween. The rubber elements 15, 15' . . . 15n which are alone deformable, are reduced in length and consequently increase in diameter; this action locks the tool rigidly in its bore, the locking effect being in proportion to the hydraulic pressure and to the resistance of the coal. On reaching a pre-determined water pressure, the resistance of the spring 9 is overcome, the valve 10 is forced back and water is ejected at high pressure through the nozzle 7. Fig. 2 shows a supplementary extension piece for the tool, comprising a tube 30, one extremity 30' of which is threaded and is screwed into the correspondingly tapped portion 16' of connection 16. The tightness of the connection is ensured by a toric seal 32 in contact with a hexagonal nut 31 screwed home and welded at 33 to the tube 30. At its other extremity, the tube 30 is likewise threaded at 30" and is screwed into the internal threads 16'a of a connection 16a similar to the connection 16. All of these connections are preferably hexagonally constructed on the outer face to facilitate mounting and dismounting.

In this manner, as many tubular extension pieces as are required may be connected end to end, within the limits of the resistance of the materials to friction against the rocky soil and to forces of whatever kind may be encountered.

The extension piece connected to the injector is illustrated in Fig. 3. This piece comprises a tube 30a, the extremity 30'a of which is screwed into the correspondingly tapped recess in connection 34, into the threaded part 36 of which the nozzle of the injector (not illustrated) is inserted. Figs. 3 and 4 provide a detail view of a device which enables the hydraulic pressure obtaining within the tube or tubes of the tool to be relaxed when the tool ceases operation. The last connection 34 is provided with a tapped bore 37 into which the threaded extremity 38 of a valve screw 39 containing an axial bore 40 is inserted. Thereby chamber 41 of the valve is in communication with the core of the tubes of the tool and at the same time with the aperture 42 leading to the outer air. The chamber 41 has an internal thread and into this thread a milled screw 44 is inserted. The stem 44a of the screw 44 forms a sleeve within the chamber 41 and encloses the oppositely disposed stem 43a of a valve button preferably of plastic material. The head 43 of the valve button is normally under pressure in order to obstruct the passages 40 and 42. When, on ceasing operation, it is desired to relax the excess pressure within the tubes of the tool, the milled screw 44 is simply rotated sufficiently to allow the valve button 43 to yield to the internal pressure which is then reduced and water escapes through the

passages 40 and 42. The valve screw 44 is returned to its working position before the resumption of operation with the pressure medium.

I claim:

5 1. A mining tool for injecting into a bore hole a liquid at high pressure, comprising in combination: a rigid tubular body having an axial core through which the liquid is injected from an inlet end to an outlet end; at the outlet end, an abutment cap screwed on the body; valve means controlling the ejection of said liquid and adapted to seat against said outlet end; a rigid sleeve spaced from and encasing said body, forming a liquid receiving chamber around said body, said sleeve being longitudinal between said inlet and an intermediate cross-section of said body; said sleeve being adapted to move longitudinally along said body; near the inlet end of said body, a ring slidably carried by said body and screwed in the upstream end of said sleeve; between the downstream end of the sleeve and said abutment cap, a plurality of spaced deformable rings around said body; a first abutment member integral with the downstream end of said sleeve and contacting rollingly the outer surface of said body; intermediate said sleeve, a second abutment member integral and rigid with said body and bearing on the inner surface 10 of said sleeve; a resilient skirt-shaped seal around the body and adjacent said second abutment member on the downstream side thereof; intermediate said first abutment member and said seal, a radial bore in the wall of said body, aligned diametrically with a hole provided in a third abutment member locked on said body and limiting the longitudinal motion of said sleeve by engaging respectively said first abutment member and said seal; the water flowing through said core under hydraulic pressure entering said chamber through said radial hole to move said sleeve toward said outlet end before said valve means are actuated; said motion of said sleeve compressing and expanding radially said deformable rings to lock the tool in its bore.

15 2. A mining tool as claimed in claim 1, in which said first and second abutment members respectively consist of a skirt-shaped ring containing a toric seal.

20 3. A mining tool as claimed in claim 1, in which said third abutment member includes a pierced ring screwed in the wall of said body, in alignment with said radial bore.

25 4. A mining tool as claimed in claim 1, in which the inlet end of said body is threaded to receive a threaded collar, a tubular extension piece threaded at one of its ends in said collar, and comprising further a nut screwed on said piece at said end and a toric seal adjacent to and forward of said nut; said seal insuring the tightness of the connection between said piece and said collar.

30 5. A mining tool as claimed in claim 4, in which said tubular extension piece is threaded at its other end in a collar for receiving a second extension piece, the latter engaging at its inlet end a threaded collar for receiving the nozzle of the injector.

35 6. A mining tool as claimed in claim 5, in which the threaded collar at the inlet end of said second extension piece comprises a radial threaded tap, a valve threaded in said tap, having an axial bore and a lateral outlet to the atmosphere, a cap screwed in said axial bore, a milled screw at the head of said cap, and adapted to rotate said cap, whereby, upon such rotation and cessation of operations, the fluid pressure in the core of the body and pieces escapes to the outer air.
